DESIGN FOR A SHOE

Irving Lippert, New York, N. Y.

Application January 6, 1939, Serial No. 82,188

Term of patent 3½ years

To all whom it may concern:

Be it known that I, Irving Lippert, a citizen of the United States of America, residing in New York city, in the Borough of Brooklyn, county of Kings, and State of New York, have invented a new, original, and ornamental Design for a Shoe, of which the following is a specification, reference being had to the accompanying drawing, forming part thereof, wherein:

I claim:

The ornamental design for a shoe, substantially as shown.

IRVING LIPPERT.
